UNITED STATES PATENT OFFICE.

LEWIS E. WELLS, OF LITTLE HOCKING, OHIO.

LADDER RUNG AND SOCKET.

No. 890,319.

Specification of Letters Patent.

Patented June 9, 1908.

Application filed March 25, 1907. Serial No. 364,276.

To all whom it may concern:

Be it known that I, LEWIS E. WELLS, a citizen of United States, residing at Little Hocking, in the county of Washington, State 5 of Ohio, have invented certain new and useful Improvements in Ladder Rungs and Sockets; and I do hereby declare the following to be a full, clear, and exact description of the invention, such as will enable others 10 skilled in the art to which it appertains to make and use the same.

This invention has relation to ladders generally and particularly to the class known in the art as "stage" ladders.

15 It is the object of the invention to provide improvements in ladders that will avoid the boring of the side rails and yet enhance the security with which the ends of the rounds or rungs are connected therewith; also, to provide 20 means for keeping the rounds tight in their sockets; also, to provide an improved construction that will prevent the rails from spreading; also, to provide improvements that will facilitate the work of repair in case 25 of necessity; and also, to provide improvements whereby the structure may be made lighter without diminishing its strength.

The nature of the invention is ascertainable from the device portrayed in the annexed drawings, forming a part of this specification, in view of which it will first be described in detail with respect to its construction and mode of operation and then be particularly pointed out in the subjoined claims.

35 Of the drawings—Figure 1 is a front elevation of my improved ladder. Fig. 2 is a like view of the end of a round secured in a socket connected with the side rail, drawn to an enlarged scale. Fig. 3 is a transverse section 40 through one of the rungs with a part of the side of the ladder in elevation. Fig. 4 is a section on line 4—4 of Fig. 3. Fig. 5 is a side view of the end of a round. Fig. 6 is a perspective view of the two parts of a split 45 socket separated from the rail and round.

Similar numerals of reference designate similar parts or features, as the case may be, wherever they occur.

In the drawings 1 designates the side-rails 50 of a ladder, and 2 the rounds.

Instead of boring the rails and securing the ends of the rounds in said bores, I form a split socket A formed in two parts 3 and 4, each part being provided at its base with 55 right-angular foot-plate 5, perforated for the reception of screw-bolts, 6, whereby the

separate parts may be secured to the inner side of the side rails 1. When the said parts are brought together or nearly together they form a split socket for the reception of the 60 end 7 of a round 2; and in order to effect greater security and stability in the connection of the end of the round with the rail, I make the diameter of the socket greater at the point adjacent to the rail than at its inner 65 end—gradually tapering the interior from the outer to the inner end,—and I shape the end 7 of the round correspondingly—that is, I taper the end from its extremity inward to an extent corresponding 70 to the depth of the socket, thus forming a shoulder 8 on the round against which the outer ends of the socket portions 9 of the parts 3 and 4 may abut. The socketed portions have perforations formed through their 75 sides for the reception of the shanks of screw-rivets 10 that may be tapped into the ends 7 of the rounds.

By the means described it will be seen that the ends of the rounds will be held in the 80 sockets with the utmost security and that weight or stress being brought to bear on the rounds will tend rather to draw the side rails together than to allow them to spread. Should there be a tendency of the parts to become loose by reason of the shrinkage of 85 wood, or from other cause they can readily be tightened by turning up the screw-bolts or rivets. The socket being split in structural character, it can readily be adjusted to variations in the sizes of the ends 7, and the parts can be applied and removed with the greatest ease and convenience.

It is proposed to supply the parts 3 and 4, which are identical in form in varying sizes, 90 if need be, ready for application to side rails of varying sizes and strengths. It is also proposed to make and sell the rounds, constructed as described separately from the split sockets, but for use with the same. 95

100 What is claimed is—

1. A socket for securing the ends of a round of a ladder to the side rails comprising two similar parts each forming one-half of a socket of larger diameter interiorly at its 105 outer than at its inner end, gradually tapering from the outer to the inner end, a laterally extended foot plate being formed on the outer end of each pair of parts, extending in opposite directions and in the same plane and perforations formed through the foot plate and side of the socket part. 110

2. A socket for securing the ends of the round of a ladder to the side rails, consisting of a split socket having an interior diameter gradually tapering from its outer to its inner end, and each split part being provided with a foot-plate extending in the same plane but in opposite directions.

3. In a ladder, the combination of the side-rails and rounds, of a socket device for attaching each end of each round to the side rails, the said rails being imperforate at the ends of the rounds, the socket device comprising two parts, each forming one-half of the socket, the latter being of larger diameter 15 interiorly at its outer than at its inner end and tapering gradually inward from the outer end, an angular foot-plate being formed on the outer end of each part adapted to fit on the inner face of the side rail and perforated 20 to receive a screw to fasten it to the rail, the end of the round received in the socket being tapered correspondingly to the taper of the socket, and the socket being inset in the end to bring its outside surface flush with the out- 25 side of the adjacent part of the round.

4. In a ladder, the combination of the side rails and rounds, of a socket-device for attaching each end of each round to the side-rails, the said rails being imperforate at the ends of the rounds, the socket device comprising two parts, each forming one-half of the socket, the latter being of larger diameter 30 interiorly at its outer than at its inner end and tapering gradually inward from the outer end, a foot-plate being connected with each part and extending therefrom in opposite directions but in the same plane to fit on the inner face of the side rail and perforated 35 to receive a screw fastened to the rail, the end of the round received in the socket, being tapered correspondingly to the taper of the socket, and the socket being inset in the end to bring its outside surface flush with the outside of the adjacent part of the round.

In testimony whereof, I affix my signature, in presence of two witnesses.

LEWIS E. WELLS.
